US00D822077S

(12) **United States Design Patent** (10) Patent No.: **US D822,077 S**
(45) Date of Patent: ** Jul. 3, 2018

(54) **CUTTING INSERT**

(71) Applicant: **Mitsubishi Hitachi Tool Engineering, Ltd.**, Tokyo (JP)

(72) Inventor: **Hayato Takahashi**, Chiba (JP)

(73) Assignee: **Mitsubishi Hitachi Tool Engineering, Ltd.**, Tokyo (JP)

(**) Term: **15 Years**

(21) Appl. No.: **29/604,510**

(22) Filed: **May 18, 2017**

(51) LOC (11) Cl. **15-03**

(52) U.S. Cl.

USPC **D15/139**

(57) **CLAIM**

The ornamental design for a cutting insert, as shown and described.

DESCRIPTION

FIG. 1 is a front perspective view of a cutting insert.

FIG. 2 is a rear perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a right side elevation view thereof; and,

FIG. 8 is a left side elevation view thereof.

The broken lines shown in the drawings illustrate portions of the cutting insert that form no part of the claimed design.

1 Claim, 8 Drawing Sheets

FIG. 1

FIG. 2

FIG. 3

FIG. 4

FIG. 5

FIG. 6

FIG. 7

FIG. 8
